(57) **CLAIM**

The ornamental design for a foldably constructed pallet support column, as shown and described.

DESCRIPTION

FIG. 1 is an isometric view of a foldably constructed pallet support column connected and hidden by a pallet top and a pallet bottom.

FIG. 2 is an exploded isometric view of FIG. 1.

FIG. 3 is an isometric view of the foldably constructed pallet support column.

FIG. 4 is a right side elevation view of the foldably constructed pallet support column of FIG. 3.

FIG. 5 is a left side elevation view of the foldably constructed pallet support column of FIG. 3.

FIG. 6 is a front elevation view of the foldably constructed pallet support column of FIG. 3.

FIG. 7 is a rear elevation view of the foldably constructed pallet support column of FIG. 3.

FIG. 8 is a top plan view of the foldably constructed pallet support column of FIG. 3; and,

FIG. 9 is a bottom plan view of the foldably constructed pallet support column of FIG. 3.

The broken lines showing a pallet top, a pallet bottom, and multiple pallet support columns in FIGS. 1 and 2 depict environment and form no part of the claimed design. All other dashed lines in the drawings depict portions of the foldably constructed pallet support column and form no part of the claimed design.

The dash-dot broken lines in FIGS. 2-9 illustrate boundaries of the foldably constructed pallet support column and form no part of the claimed design.
